US00D906750S

(12) **United States Design Patent** (10) Patent No.: **US D906,750 S**
(45) Date of Patent: **** Jan. 5, 2021**

(54) **COFFEE MAKER AND COMPONENTS THEREOF**

(71) Applicant: **SharkNinja Operating LLC**, Needham, MA (US)

(72) Inventor: **Dan Kestenbaum**, Brookline, MA (US)

(73) Assignee: **SHARKNINJA OPERATING LLC**, Needham, MA (US)

(**) Term: **15 Years**

(21) Appl. No.: **29/649,477**

(22) Filed: **May 30, 2018**

(51) LOC (13) Cl. **07-01**

(52) U.S. Cl.

USPC **D7/309; D7/311**

(58) **Field of Classification Search**

(57) **CLAIM**

The ornamental design for coffee maker and components thereof, as shown and described.

DESCRIPTION

FIG. 1 is a perspective view of a coffee maker and components thereof, showing our new design;

FIG. 2 is a front view of the embodiment shown in FIG. 1; FIG. 3 is a rear view of the embodiment shown in FIG. 1; FIG. 4 is side view of the embodiment shown in FIG. 1; FIG. 5 is another side view of the embodiment shown in FIG. 1;

FIG. 6 is a top view of the embodiment shown in FIG. 1; FIG. 7 is a bottom view of the embodiment shown in FIG. 1; and,

FIG. 8 is another perspective view of the embodiment shown in FIG. 1.

The broken lines in the figures are for environmental purposes only and form no part of the claimed design.

1 Claim, 8 Drawing Sheets
